STEVE OLIVER, OF WHIPPLE BARRACKS, ARIZONA.

COMB.

Application filed March 25, 1922. Serial No. 546,697.

To all whom it may concern:

Be it known that I, STEVE OLIVER, a citizen of the United States, residing at Whipple Barracks, in the county of Yavapai and State of Arizona, have invented new and useful Improvements in Combs, of which the following is a specification.

This invention relates to improvements in combs and has for an object the provision of a comb which may be conveniently carried in the pocket of a garment and there held against accidental loss.

Another object of the invention is the provision of a pocket comb which is constructed from a single piece of material and which includes means for yieldingly engaging the pocket to hold it in place in a manner to permit of its ready removal.

With the above and other objects in view, the invention further includes the following novel features and details of construction, to be hereinafter more fully described, illustrated in the accompanying drawings and pointed out in the appended claims.

25 In the drawings:—

Referring to the drawings in detail, wherein like characters of reference denote corresponding parts, the comb as shown in the drawings comprises a back 10, from one side edge of which extends teeth 11. The comb may be made from any suitable material and is preferably formed from a single piece of material, the back of the comb being extended in tapered formation and bent over upon itself to provide a clip 12, which is preferably of a resilient character. The extremity of this clip may be 40 formed in any manner to provide a rounded surface for engagement with the side of the pocket of the garment, or, if desired this extremity may be provided with a ball 13.

It will be seen from the foregoing description and the accompanying drawings, that the invention provides a comb which may be conveniently carried in the vest pocket of a garment in a manner to prevent loss and to prevent injury to the garment. 50

The invention is susceptible of various changes in its form, proportions and minor details of construction and the right is herein reserved to make such changes as properly fall within the scope of the appended 55 claims.

Having described the invention what is claimed is:—

1. A pocket comb formed from a single piece of material and including a back, teeth 60 extending from one edge of the back and a clip formed by extending the back and bending the extension formed upon itself.

2. The combination with a comb, of means formed integral with and extending from 65 one end of the comb back to provide a retaining clip.

In testimony whereof I affix my signature.

STEVE OLIVER.
